(57) **CLAIM**

The ornamental design for a hook-type brassiere-strap link, as shown and described.

DESCRIPTION

FIG. 1 is a perspective view of a hook-type brassiere-strap link according to our new design;

FIG. 2 is a front elevational view thereof, the back view being a mirror image; and,

FIG. 3 is a right-hand side elevational view, the left side being unornamented.

1 Claim, 1 Drawing Sheet**FIG. 1**

FIG. 2

FIG. 3
